UNITED STATES PATENT OFFICE.

HARRY GRASS, OF DETROIT, MICHIGAN.

BOTTLE-WASHER BRUSH.

1,306,478.

Specification of Letters Patent. Patented June 10, 1919.

Application filed August 28, 1918. Serial No. 251,723.

To all whom it may concern:

Be it known that I, HARRY GRASS, a citizen of the United States of America, residing at Detroit, in the county of Wayne and

5 State of Michigan, have invented certain new and useful Improvements in Bottle-Washer Brushes, of which the following is a specification, reference being had therein to the accompanying drawings.

10 Machines employed for washing bottles, particularly beverage bottles, have reciprocable tubular spindles with the ends thereof provided with brushes and when a spindle is reciprocated the brush on the end thereof 15 is adapted to enter the bottle and thoroughly clean the inner walls thereof as water or washing compound is injected into the bottle. Some brushes are in the form of flexible pieces of rubber, others of bristles loosely 20 or fixedly held relative to the spindle, and my invention has special reference to bristle brushes that are self adjusting relative to a bottle and have a limited movement relative to a machine spindle.

25 The object of my invention is to provide a simple, durable and inexpensive spindle brush that may safely enter a bottle and be readily withdrawn therefrom, the brush being of such design as to thoroughly cleanse 30 the inner walls of the bottle during the injection of water therein:

The above and other objects are attained by a mechanical construction that will be hereinafter specifically described and then 35 claimed, and reference will now be had to the drawing, wherein—

Figure 1 is a plan of a bottle washer brush in accordance with my invention;

Fig. 2 is a longitudinal sectional view of 40 a portion of the brush spindle showing brush arms;

Fig. 3 is a side elevation of the same; and

Fig. 4 is a developed view of one of the brush arms.

45 In the drawings, 1 denotes a conventional form of tubular machine spindle having a detachable head 2 provided with an outlet port 3 for the ejection of water supplied to the head 2 by the spindle 1.

50 The outer end of the head 2 is bifurcated or slotted, as at 4 and provided with a transverse pivot pin 5 for parallel brush arms or members 6. Each brush arm or member is made from a flat oblong piece of sheet metal

that is bent on itself at a longitudinal central imaginary line 7, so as to provide parallel opposed side wings 8. It is between the side wings of the brush arm that a row of bristles 9 have the inner ends thereof clamped so that the outer ends will present 55 a straight edge, and in the outer end of the arm are bunched the inner ends of bristles 10, said bristles being disposed so that the outer ends thereof will be in an arc from the straight edge of the bristles 9. The 60 bristles 10 are furthermore disposed so that when the brush arms 6 are brought into parallelism, the bristles 10 will be bunched in the longitudinal axis of the spindle 1. The bristles 9 and 10 may be held by compressing 65 the opposed side wings 8 of each arm and in addition to such holding means the outer ends of the arms may be provided with rivets 11 positively holding the side wings 70 in close proximity to each other.

The inner ends of the arms 6, which are pivotally held on the pin 5, abut angularly disposed shoulders 12 formed by providing the outer end of the head 2 with kerfs 13, said kerfs providing clearance for the inner 80 ends of the arms 6 when said arms are closed or in parallelism, while the shoulders 12 limit the opening movement of the arms 6 and maintain the same at an obtuse angle relative to each other, that is, with the 85 brushes spread apart as shown in Fig. 1. The kerfs 13 are necessarily disposed the reverse of each other, as shown in Figs. 2 and 3 and the outlet port 3 is located at one side of one of the kerfs.

I attach considerable importance to the 90 simplicity of construction entering into each brush arm, and when the spindle is revolved within a bottle, the bristles 9 and 10 will thoroughly cleanse the interior surfaces of 95 the bottle.

One embodiment of my invention has been illustrated but it is to be understood that the structural elements are susceptible to such variations and modifications as fall 100 within the scope of the appended claim.

What I claim is:—

A bottle washing brush comprising a spindle head having communicating kerfs and a water outlet port with said kerfs 105 forming reversely disposed shoulders, sheet metal arms having compressed inner ends thereof pivotally mounted in the kerfs of

said head to engage the kerf shoulders and thereof in retaining said bristles in said arms. 10
each arm providing opposed parallel wings, brush bristles having the inner ends thereof between the wings of each arm and some of said bristles disposed in a row and others bunched at the outer end of the arm, and means in the outer ends of said arms coöperating with the compressed inner ends

In testimony whereof I affix my signature in the presence of two witnesses.

HARRY GRASS.
